UNITED STATES PATENT OFFICE

JAMES COOPER, OF SOLVAY, NEW YORK, ASSIGNOR TO HALL & MCCHESENEY, INC., OF SYRACUSE, NEW YORK, A CORPORATION OF NEW YORK

LOOSE LEAF BINDER

Application filed November 20, 1930. Serial No. 496,970.

This invention relates to a new and improved loose leaf binder.

The main object of my invention is to provide a loose leaf binder which has a metal back and which is of such a design that it can be made and assembled quickly and cheaply.

Other objects and advantages relate to the size, shape and arrangement of parts, all as will more fully appear from the following description taken in connection with the accompanying drawings in which:—

Figure 1 is a perspective view, partially broken away and partially in section, of a binder embodying my invention.

Figure 2 is a section on line 2—2 of Figure 1.

Figure 3 is a perspective view of a binder embodying a modified form of my invention.

Figure 4 is a section on line 4—4 of Figure 5.

Figure 5 is a section on line 5—5 of Figure 3.

Figure 6 is a section similar to Figure 5 with the covers of the binder in the open position.

Figure 7 is a detail transverse section taken through one edge of the back members, illustrating the hinged connection of the spacing strips shown in Figures 5 and 6.

My improved binder comprises opposed housings 1 and 2, opposed covers 3 and 4, a main back plate 5, and a supplementary back plate 6.

Housing 1, cover 3 and one longitudinal edge of back plate 5 are provided with tubular extensions which encircle a rod 7.

The tubular extensions on the three members just mentioned are in staggered relation to form a piano hinge.

Similarly, housing 2, cover 4 and the opposite longitudinal edge of back plate 5 have tubular extensions which encircle a rod 8 to form a piano hinge.

Back plate 6 has secured, as by riveting, thereto in spaced relation adjacent one end thereof, a pair of upwardly extending posts 9 and 10. Posts 9 and 10 are internally threaded.

A similar pair of posts, not shown, are se-

cured adjacent the opposite end of back plate 6. Back plate 6 is preferably provided with depressions at the points where the posts as 9 and 10 are secured so that the riveted heads of such posts will not extend beyond back member 6.

Back plate 5 is provided with apertures through which bolts 11 and 12 extend. Bolt 11 is threaded into post 9 and bolt 12 is threaded into post 10 to secure the back plate 6 to back plate 5.

Similar bolts, not shown, are provided for the purpose of engaging the posts at the opposite end of back plate 6. Back plate 5 is preferably provided with depressed portions 13 and 14 so that the heads of the bolts will be countersunk to bring them level with the upper face of back plate 5.

Back plate 6 has a facing 15 of leather or other appropriate material corresponding to the facings 16 and 17 on covers 3 and 4.

A plurality of posts 18 have their opposite ends extending into apertures in housings 1 and 2. Posts 18 are provided with apertures in their ends in which are removably positioned rods 19 and 20 to releasably hold posts 18 in position in housings 1 and 2.

In the modified form shown in Figures 3 to 6, housing 1, cover 3 and back plate 5 are secured together with the piano hinge above described.

Similarly, housing 2, cover 4 and back plate 5 are secured together by a piano hinge.

For the purpose of securing back plate 6 in position, I provide adjacent one edge thereof, a longitudinally extending member 22 secured to back plate 6 as by welding.

Member 22 has a plurality of spaced tubular portions incorporated into the piano hinge by which housing 1, covering 3 and back plate 5 are secured together.

A similar member 23 is provided on the opposite edge of back plate 6 and carries tubular portions which are incorporated into the piano hinge by which housing 2, cover 4 and back plate 5, are secured together.

The longitudinal edges of back plate 6 extend outwardly in juxtaposition to the rear edges of the covers 3 and 4 leaving only enough clearance between the back plate 6

and the covers 3 and 4 to permit the manipulation of the covers above their respective hinges.

For the purpose of rigidity and in order that the structure may resist the shocks to which it is subjected in use, I prefer to make back plates 5 and 6 of metal although other materials may be employed.

I have here shown a particular arrangement of parts as an exemplification of an embodiment of my invention, but I do not desire to restrict myself to the exact size, shape or relation of parts as various changes may be made within the scope of the appended claims.

I claim:

1. In a loose leaf binder, a back member, a housing hinged to each longitudinal edge of the back member, opposed covers hinged to the back member, a plurality of posts connecting the housings, and a supplementary back member rigidly held in spaced relation to the first named back member.
2. In a loose leaf binder, a back member, a housing hinged to each longitudinal edge of the back member, opposed covers hinged to the back member, a plurality of posts connecting the housings, a supplementary back member, a plurality of posts on the supplementary back member, and means for securing the posts to the first named back member.
3. In a loose leaf binder, a back member, a housing hinged to each longitudinal edge of the back member, opposed covers hinged to the back member, a plurality of posts connecting the housings, a supplementary back member, a plurality of posts on one of the back members, and means for securing the posts to the other back member.
4. In a loose leaf binder, a back member, a housing and a cover joined together on a piano hinge, a second housing and a second cover joined to the back member on a second piano hinge, a plurality of posts connecting the housings, a supplementary back member, opposite strips each having one edge secured to the supplementary back member and having the other edge incorporated in one of the piano hinges.

In witness whereof I have hereunto set my hand this seventeenth day of November, 1930.

JAMES COOPER.
